[57] CLAIM

The ornamental design for a baking and proofer oven, as shown and described.

DESCRIPTION

FIG. 1 is a front elevational view of a baking and proofing oven showing my new design;

FIG. 2 is a side elevational view thereof, the opposite side being a mirror image;

FIG. 3 is a rear elevational view thereof;

FIG. 4 is a top plan view thereof;

FIG. 5 is a front elevational view of a second embodiment thereof;

FIG. 6 is a side elevational view thereof, the opposite side being a mirror image;

FIG. 7 is a rear elevational view thereof;

FIG. 8 is a top plan view thereof;

FIG. 9 is a top, front and side perspective view of a third embodiment thereof;

FIG. 10 is a front elevational view thereof;

FIG. 11 is a top plan view thereof;

FIG. 12 is a rear elevational view thereof;

The undisclosed side of the third embodiment is shown in FIG. 6.
